UNITED STATES PATENT OFFICE.

MARTIN L. RINEHART, OF RICHMOND, OHIO.

PLOW.

SPECIFICATION forming part of Letters Patent No. 310,227, dated January 6, 1885.

Application filed July 21, 1884. (No model.)

To all whom it may concern:

Be it known that I, MARTIN L. RINEHART, a citizen of the United States, residing at Richmond, in the county of Jefferson and State of Ohio, have invented certain new and useful Improvements in Plows; and I do hereby declare that the following is a full, clear, and exact description of the same, reference being had to the annexed drawings, making a part 5 of this specification, and to the letters and figures of reference marked thereon, in which—

Figure 1 is a side elevation looking from the mold-board side. Fig. 2 is a side elevation looking from the opposite side. Fig. 3 is a 15 top view; and Fig. 4 is a longitudinal section on lines $\alpha\alpha$, Figs. 1 and 2.

The present invention has relation to the general improvement in plows; and its nature consists in providing a landside formed in sections, and in providing a peculiarly-formed mold-board, and in providing a cutter or jointer, formed substantially as shown, and in the several parts and combination of parts hereinafter described, and pointed out in the 25 claims.

Similar letters of reference indicate corresponding parts in the drawings.

In the accompanying drawings, A represents the mold-board, which is substantially 30 of the form shown in the drawings, and is attached to the post or standard B by suitable clamping bolts or rivets, said post or standard being recessed, so as to receive the forward end of the mold-board, and bringing the top 35 or upper portion of said post or standard flush with the working-surface of the mold-board. The forward end of the mold-board is formed beveling, so as to form a recess to receive the rear portion of the cutter or jointer C, as seen 40 in Figs. 1 and 2. The portion of the post or standard B abutting against the cutter or jointer C is formed beveling, which completes the recess, so as to hold the cutter or jointer in proper position laterally. The forward 45 portion of the mold-board is slightly concaved, as seen in Fig. 4, the rear portion being convexed, as seen in said Fig. 4. These curves are the greatest at the lines $\alpha\alpha$, Figs. 1 and 2, and gradually decrease toward the top 50 until the top or upper portion of said mold-

board assumes a straight line. The post or standard B is substantially of the form shown in the drawings, the bottom or lower portion being formed so as to attach the share, landside, and mold-board in the ordinary manner. This post or standard is provided with the recess b, which is for the purpose of receiving the arm c and the key D. The recess b and the arm c are formed dovetailed, so as to securely hold the cutter or jointer C 55 in proper position by means of the key D, which is also formed dovetailed. The forward portion of the cutter or jointer C is formed straight when it is designed to be used in plowing sod. In plowing loose ground a 60 cutter or jointer having a curved edge, as indicated by the dotted lines in Figs. 1 and 2, should be used. The landside proper is formed in two sections or pieces, E and F, and are attached to the post or standard by suitable 65 clamping-bolts, as seen in Fig. 2. The top or upper section is provided with one or more arms, to which the lower section is bolted or riveted.

The object of forming the landside in sections is to form a landside high enough, so that no dirt will fall over said landside, and, as it will be seen that the lower portion of the landside will wear much faster than the upper portion, a new section or piece can be supplied 80 at a much less expense than when the entire landside is formed in one piece.

The share G is substantially of the form shown in the drawings, and is provided with the recess H, which comes in line with the recess formed by the mold-board and standard, and is for the purpose of receiving the cutter or jointer C, as shown in the drawings.

It will be seen that by providing a high mold-board and landside no dirt or clods will 90 fall over said parts into the furrow. It will also be seen that by attaching the cutter or jointer as shown and described no dirt can be collected and held by said cutter or jointer.

Having now fully described my invention, 95 what I claim as new, and desire to secure by Letters Patent, is—

1. The combination, with the standard B, formed with the dovetailed recess b, of the share G, formed with the recess H, as shown, 100

- the cutter C, fitting in the recess H of the share, with a dovetailed arm, c, fitting in recess b, and dovetailed key D, fitted in said recess against said arm, substantially as described.
- 5 2. The combination of the mold-board A, formed straight upon its upper portion, and its working-surface being concaved in forward section and convexed in rear section, said curves being greatest on lines $x\ x$ and gradually decreasing toward its top, of the share G, having the recess H, and the cutter or jointer

C, provided with the arm c, engaging with the post B, having dovetailed recess b, substantially as and for the purpose set forth.

In testimony that I claim the above I have 15 hereunto subscribed my name in presence of two witnesses.

MARTIN L. RINEHART.
